UNITED STATES PATENT OFFICE.

ALEXANDER T. BROWN, OF SYRACUSE, NEW YORK.

DESIGN FOR A TYPE-BAR FOR TYPE-WRITING MACHINES.

SPECIFICATION forming part of Design No. 33,736, dated December 18, 1900.

Application filed August 17, 1899. Serial No. 727,593. Term of patent 14 years.

To all whom it may concern:

Be it known that I, ALEXANDER T. BROWN, a citizen of the United States, and a resident of Syracuse, in the county of Onondaga and State 5 of New York, have invented a certain new, useful, and original Design for a Type-Bar for Type-Writing Machines, of which the following is a specification, reference being had to the accompanying drawings.

Figure 1 is a perspective view of a type-bar, showing my new design. Fig. 2 is a sectional view taken on line X X of Fig. 1.

As shown in the drawings, the leading or material feature of my design consists of a 15 type-bearing stem 1, which is formed at its rear end with an enlarged ring 2, which is pro-

vided interiorly—that is, between its lateral faces or sides—with a circular or annular groove or depression 3, extending into the body of the ring.

What I claim as new, and desire to secure by Letters Patent, is—

The design for a type-bar, substantially as herein shown and described.

Signed at Syracuse, in the county of Onondaga and State of New York, this 8th day of August, A. D. 1899.

ALEXANDER T. BROWN.
